ATTORNEYS.

UNITED STATES PATENT OFFICE.

MICHAEL F. DEAN, OF INDIANAPOLIS, INDIANA.

PRINT OR FILM HOLDER.

Application filed March 14, 1927. Serial No. 175,403.

This invention relates to a holder for small X-ray films or prints, particularly those of teeth.

The chief object of the invention is to provide a support for a film or print of the character indicated that does not require a covering for the holder aperture.

Another object of the invention is to provide a holder which is adapted to support a plurality of films and progressively expose the same for observation.

One feature of the invention, in addition to the accomplishment of the foregoing object, consists in the mounting of a multiple holder in a container and providing upon the face of said container suitable lines arranged to receive data relative to the print or prints mounted in the holder.

The full nature of the invention will be understood from the accompanying drawings and the following description and claims:

In the drawings Fig. 1 is a front view of a holder of the character indicated. Fig. 2 is a vertical section taken on line 2—2 of Fig. 1 and in the direction of the arrows. Fig. 3 is a developed view of the blanks forming the multiple holder.

In the drawings 10 indicates a pair of discs maintained in spaced relation by the blank portions 11 in the form of segments and the central portion 12 in the form of a star. The spacers 11 and 12 may be formed from a single sheet of cardboard or the like. Between each pair of adjacent segments 11 there is formed a radial passage or groove 13. Each circular disc 10 is provided with cut-outs 14 that are adapted to register with each other and register with the groove and be positioned therein such that a ledge is formed upon the inner end and opposite sides of the cut-outs in spaced relation to the segments and the star. Herein six receiving pockets are provided in the disc holder. The film which is of standard size, approximately one inch by one and one-half inches in length, is positionable in this groove by being passed into the same through the peripheral mouth 15. In order to secure rigidity until the holder is to be utilized the cut-outs in each disc may be but partially severed so that pressing through the same will remove the cut-out portion or blank. The film can thereupon be inserted and the holder interposed between the observer and a source of strong light for observation.

From the foregoing it will be noted that the

holder is adapted to contain sufficient film for a full set of teeth and that no transparent cover is required for the aperture as heretofore has been employed.

A case may be provided for the holder if desired and herein the same is shown substantially square and it consists of an elongated blank folded at its mid-portion as at 16 to provide a front face 17 and a back face 18. Extending through the circumscribed square is the retainer and pivot forming member 19 which pivotally supports the multiple disc holder described. The two sides 17 and 18 at their adjacent unattached ends are secured together by suitable means 20 to form a casing for the multiple disc holder. The multiple disc holder intermediate its ends, upon opposite sides, is cut out as at 21 to expose a portion of the disc holder for finger engagement so that the disc holder can be rotated to expose the respective films mounted therein through an aperture 22 formed in each face of the case and in registration with each other. The front face of the case includes an aperture 23 through which a numeral designation carried by the disc is exposed and in opposed relation adjacent said aperture 22 is a legend therefor. The upper part of the case may be suitably lined and printed to contain information relative to the patient. The lower portion of the case may be similarly provided with a chart to receive information disclosed by the films. If the holder is not loaded prior to mounting in the case, the holder may be loaded by positioning the mouth 15 in registration with one of the cut-outs 21 and radially sliding the film into the pocket or groove 13 and if it does not seat as shown in Fig. 3, the film therein being shown dotted and indicated by the numeral 30, the same may be seated by engaging the film when it is exposed through the registering apertures 22.

The invention claimed is:

1. A holder of the character indicated, comprising a pair of casing forming plate portions each including an aperture registering with a corresponding aperture in the other, and a film and print holder pivotally supported therebetween and having a portion projecting beyond the same for finger engagement, said holder comprising a plurality of plates, each apertured and with the apertures registering with each other and adapted to register with the first-mentioned plate registering apertures, and spacing means between

said holder forming plates for forming a plurality of grooves therebetween each registering with one of the holder plate registering apertures for X-ray film and print reception, exposure and examination.

2. An X-ray film and print holder including a casing having a front and back with a pair of registering openings therein, suitable rulings on the face of said casing for receiving a record relative to the print and film mounted therein, and a print and film holder movably supported thereby including a pair of plates in spaced relation with registering apertures therein for X-ray print reception adapted to register with the casing apertures for print examination.

3. An X-ray print and film holder comprising a pair of plate portions in spaced relation, each including an aperture adapted to register with the other for the transmission of light therethrough, said plate portions being suitably cut away at the periphery and a multiple print or film holder comprising a pair of plates secured in spaced relation including a plurality of radial grooves there-

between and arranged in spaced relation about a common axis and equidistant therefrom, said last-mentioned spaced plates each including a similar number of apertures, adjacent apertures registering with each other and the grooves, and means pivotally supporting said grooved and apertured plates between said first-mentioned plate portions, whereby each of the registering pair of apertures of the spaced plates and groove is adapted to successively register with the registering apertures of the first-mentioned plate portions, the latter being suitably cut away to expose a portion of the second-mentioned plates for rotating the second-mentioned plates within the first-mentioned plates, said cut away portions being of such character as to permit the radial reception of prints into the groove of the second-mentioned plate portions for registration with the apertures thereof.

In witness whereof I have hereunto affixed my signature.

MICHAEL F. DEAN.
